REISSUE

MILLING-MACHINE.

1,178,270.

Specification of Letters Patent.

Patented Apr. 4, 1916.

Application filed June 30, 1915. Serial No. 37,246.

To all whom it may concern:

Be it known that we, CHARLES H. SCHURR and ERNEST J. LEES, citizens of the United States, residing at Cleveland, in the county of Cuyahoga and State of Ohio, have invented a new and useful Improvement in Milling-Machines, of which the following is a specification, the principle of the invention being herein explained and the best mode in which we have contemplated applying that principle, so as to distinguish it from other inventions.

Our invention deals with an improvement in milling machines and more particularly to the relative actuation and control of certain parts thereof.

Heretofore, so far as our knowledge extends, whenever a milling tool had concluded a given cut incident to the travel of its supporting carriage in predetermined harmonious relation to the rotation of the work spindle, it was required preparatory to a subsequent cut to reverse or release the interconnecting mechanism necessitating a release of the operative tension or torque between the several coacting parts of such mechanism. This circumstance entailed a "picking-up" action of such parts for each individual cut with consequent wear upon the parts, surprising waste of time and frequent inaccuracies.

The object of this invention is to provide an arrangement which will avoid the stated factors of demerit in a feasible and at the same time simple manner. We accomplish such object according to the exemplification of the drawings by the employment, as one part of the interconnecting mechanism, of a spline shaft along which an auxiliary slide which indirectly supports the tool carriage may be returned without disturbing the established tension which the driving parts had to assume in the beginning.

Concrete illustrations which indicate the value of our discovery may be helpful: (a) Owing to the avoidance of any save initial lost motion for any particular job the relative rotation of the work spindle and lead screw can be more reliably depended on. (b) Owing to the possible distribution of the driving contact over a longer or full section of the lead screw instead of repeatedly over some specific part thereof, absolute accuracy may be expected. (c) Owing to an immediately effective driving response our conception enables

the operator to start the rotation and lead at the same time. The advantage of this will be clearly understood when cutting a thread in a closed bore where it is highly desirable to effect the cutting of the first thread, without an error.

With the foregoing and other objects in view the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

Adverting to the drawings: Figure I is a top plan of a milling machine embodying our invention. Fig. II is a section on line II II of Fig. I. Fig. III is a section on zig-zag line III III of Fig. II. Fig. IV is a section of a common locking detail taken on line IV IV of Fig. I. Fig. V is a broken front elevation of certain auxiliary actuating mechanism.

Inasmuch as comparatively few parts of the machine in its entirety have any direct bearing upon the invention, designation by reference numeral in the drawings will be restricted to mention only of such as are essential to an understanding of our control of certain compound actions. In order to avoid any possible confusion it should be borne in mind moreover, that we have elected to call the members which are required to direct the "feed" and "lead" as the "tool carriage" and "longitudinally movable slide" respectively. As has been earlier stated the drawings exemplify as one feature of our invention a coacting member capable of having independent movement imparted to it and to this we will hereinafter refer as the "auxiliary slide." So, the term "feed" should be considered as that movement which is established in predetermined harmony with the rotation of the work. The term "traverse" will be employed throughout to indicate relative movement of the work and tool in a longitudinal direction, that is, parallel to the axis of the work spindle, whether effected by power or hand, but regardless of the rotation of the work.

A bed 1 carries above the drive pulley 2 which effects the rotation of the shaft 3, pinion 3^a and gear 3^b. The shaft 3 operates

the work spindle 4 in the head stock 5. The work W is secured in a suitable collet 6 as clearly appears in Fig. III. The drive is communicated from the work spindle 4 through the usual chain of gears 7, 8 and 9 to another shaft 10 which in accordance with our invention is of the spline type. This latter in turn rotates a pinion 11 which meshes with an idler 12, suitably carried upon a conveniently located stud and by this means drives another pinion 13 loose upon the lead screw 14 which is mounted in an approved manner for imparting longitudinal movement to a slide 15 in harmony with the rotation of the work. At the same time our lead screw 14 is purposely not permanently anchored to the bed. We have enabled driving of the screw 14 by the pinion 13 through the agency of a hand wheel 16 which is not only keyed and slidably mounted upon the end of the lead screw 14, but also adapted to have a jaw clutch connection 16a with the pinion 13 as appears in Fig. III. The actuation of the lead screw 14 contrives to effect the traverse of the slide 15 which supports the tool carriage 17 with its center 18 and tool designated as T. By this arrangement on inconsequential occasion the operator may still disengage the clutch and actuate the wheel 16 to traverse the slide 15 back again as heretofore necessitated. When however a given cut is unfinished such a reversal of the traverse and release of torsion makes back lash unavoidable upon completion of the cut. This back lash occasions inaccuracies for which it is very difficult to compensate. Our invention makes it unnecessary to release such torsion in the parts regardless of the distance to be traversed. In any other machine the operator must reverse all the mechanism, or must release the driving engagement between the lead screw and the nut in which it is threaded, and thus permit back lash and torsion to occur at the end of every cut. The fact that we have an auxiliary slide eliminates this detriment.

According to the illustrated exemplification of our invention, instead of having the slide 15 feed along the bed we interpose a second or auxiliary supporting slide 19 adapted for traverse in the same general direction, as is indicated in Fig. II. This auxiliary slide 19 is operatively associated with the spline shaft 10 along which it is slidable or with reference to which it may be fixed by locking to the bed through the agency of the well known clamp 20 having a locking lever 20a shown in Figs. I and IV. It is therefore the auxiliary slide 19 and not the bed 1 which directly supports the slide 15. Hence when the auxiliary slide 19 moves the slide 15 moves with it. When the auxiliary slide is locked to the bed it of course constitutes in effect a part thereof.

When on the other hand it is unlocked, a longitudinal traverse may be imparted thereto in the following manner: A lower hand wheel 21 turns a shaft 22, pinion 23 and compound gear 24. This latter engages with a rack 25 shown in Figs. II and V thus causing the auxiliary slide 19 to traverse and carry the pinion 11 along with it without necessitating a reversal of the driving tension either in such pinion or any other part of the mechanism for establishing the harmonious connection between the work and lead screw 14. It will now be clear that a relative movement of the work and tool toward or away from each other may be brought about independently of any rotation of the lead screw 14, and independently of any rotation of the pinion 11, indeed, independently of the reverse rotation of any other part of the aforementioned mechanism. In this way back lash is avoided.

It is apparent that the auxiliary slide may be locked at any point preparatory to commencing or recommencing a cutting operation, and thereafter caused to move rapidly traverse in the return direction by the manipulation of the wheel 16 to bring a different section of the lead screw into working engagement. While eventually torque has to be released with our arrangement, the "picking up" as an incident thereto is at comparatively long intervals with a pronounced saving of time and wear.

We claim:

1. In a milling machine, the combination of a bed, a work part rotatably mounted thereon, a movable tool part, a traversing slide supporting one of said parts, means for actuating the other of said parts, mechanism synchronously connecting such other part with said slide whereby automatically to traverse the same in predetermined ratio, and an auxiliary traversing slide supporting the first mentioned slide and adapted to be fixed relative to the bed during the automatic traverse and to be loosened and bodily traversed in the reverse direction to carry said first mentioned slide along with it without either reversing or disconnecting said mechanism preparatory to performing a succeeding cutting operation whereby to avoid back lash during such automatic traverse.

2. In a milling machine, the combination of a bed, a work part rotatably mounted thereon, a movable tool part, a traversing slide supporting one of said parts, means for actuating the other of said parts, mechanism synchronously connecting such other part with said slide whereby automatically to traverse the same in predetermined ratio, said mechanism including a lead screw operatively engaging said slide, and an auxiliary slide interposed between said bed and first mentioned slide, said auxiliary slide being

in sliding connection below with said bed and above with said first mentioned slide, said mechanism also including a spline shaft, and pinion carried by said auxiliary slide 5 and movable along such shaft, whereby said auxiliary slide and hence said first mentioned slide and tool may be traversed without disturbing said lead screw connection.

3. In a milling machine, the combination 10 of a work spindle, a tool spindle, a slide supporting one of said spindles, a harmonious connection including a lead screw between said slide and the other of said spindles adapted automatically to translate the rotation 15 of the latter into a predetermined ratio of forward traverse of the slide, and a device for effecting the concerted reverse traverse of said lead screw and slide without disconnecting, or releasing the tension 20 in, said mechanism.

4. In a milling machine, the combination of a work spindle, a tool spindle, a slide supporting one of said spindles, mechanism connecting said slide and the other of said spindles and adapted automatically to translate the rotation of the latter into a predetermined ratio of forward traverse of said slide, said mechanism including a pair of 25 members capable of relative movement distinct from their coacting movement as parts of the automatic operation of such mechanism, and means for accomplishing such distinct movement whereby to traverse said 30 slide without disconnecting or reversing any part of said mechanism.

5. In a milling machine, the combination of a work spindle, a tool center, a traversing slide supporting the latter, and mechanism including a lead screw operatively connecting said spindle and slide and adapted automatically to effect the working traverse of 40 said slide in a given direction, means for reversing the direction of rotation of said screw to effect the idle traverse of said slide in the opposite direction, and distinct means 45 for effecting the traverse of said slide independently of any disconnection from and independently of any rotation of said lead screw for the purpose specified.

6. In a milling machine, the combination 50 of a bed, a work spindle and a tool spindle, a slide mounted to traverse upon such bed, means for locking said slide to the bed, a slide supporting one of said spindles and mounted to traverse upon said first mentioned slide, and a connection between the other spindle and the upper slide to automatically effect a predetermined ratio of movement therebetween, said connection including a pinion carried by said lower slide 55 and also including a spline shaft along which said pinion may slide and with which said pinion may rotate, whereby to traverse said lower slide counter to the automatic traverse of said upper slide without release 60 of the driving tension in said mechanism.

Signed by us this 29th day of June, 1915.

CHARLES H. SCHURR.
ERNEST J. LEES.
